US0D1076623S

(12) **United States Design Patent** (10) **Patent No.:** **US D1,076,623 S**
(45) **Date of Patent:** **** May 27, 2025**

(54) **SPEED WRENCH**

(71) Applicant: **Wanzhuo (Jiangsu) Hardware Tools Manufacturing Co., Ltd.**, Jiangsu (CN)

(72) Inventors: **Shixian Xu**, Jiangsu (CN); **Xianli Zhuansun**, Anhui (CN); **Chenggang Zhang**, Anhui (CN)

(73) Assignee: **Wanzhuo (Jiangsu) Hardware Tools Manufacturing Co., Ltd.**, Xuzhou (CN)

(**) Term: **15 Years**

(21) Appl. No.: **29/990,830**

(22) Filed: **Feb. 25, 2025**

(30) **Foreign Application Priority Data**

Dec. 27, 2024 (CN) 202430828636.X

(51) **LOC (15) Cl.** **08-05**

(52) **U.S. Cl.**

USPC **D8/23**

(58) **Field of Classification Search**

USPC D8/23, 22

CPC B25B 13/28; B25B 13/505

See application file for complete search history.

(57) **CLAIM**

The ornamental design for a speed wrench, as shown and described.

DESCRIPTION

FIG. 1 is a perspective view of a speed wrench showing our new design;

FIG. 2 is another perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof; and,

FIG. 8 is a bottom plan view thereof.

1 Claim, 8 Drawing Sheets
